UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,250,819.

Specification of Letters Patent. Patented Dec. 18, 1917.

Application filed May 31, 1916. Serial No. 100,914.

To all whom it may concern:

Be it known that I, FRANK DUTCHER, a citizen of the United States, residing at Versailles, in the county of Allegheny and State 5 of Pennsylvania, have invented certain new and useful Improvements in Railway Signal-Torpedoes, of which the following is a specification, reference being had therein to the accompanying drawing.

10 This invention relates to improvements in railway signal torpedoes, the primary object thereof is to form the case from a blank of paper so shaped that a tablet explosive can be conveniently wrapped therein and the 15 rail-engaging strap secured thereto, the blank being cemented as the tablet is wrapped therein.

In the accompanying drawing—

Figure 1 is a perspective view of a completed case containing the explosive tablet, the case being formed from a blank.

Fig. 2 is a longitudinal central vertical sectional view of Fig. 1.

Fig. 3 is a transverse sectional view on 25 the line 3—3 of Fig. 2.

Fig. 4 is a plan view of a blank in which the tablet explosive is wrapped.

Referring now to the drawings in which like reference numerals denote the same 30 parts, 1 is the case of the torpedo in its completed form with the rail engaging strap 2 extending longitudinally from its ends, for securing it to a rail 3 by bending it around the head of the rail in a manner 35 well understood by those skilled in this art.

Referring now particularly to Fig. 4, illustrating the blank from which the case is formed, this blank has an elongated body-portion 4. From one end of this body-portion 40 4, lateral flaps 5 extend in opposite directions and intermediate laterally extending flaps 6 are also provided. These flaps 6 are each provided with a strap receiving opening 7.

45 An explosive tablet 8 of rectangular form and of a length approximately equal to the width of the body portion 4 is placed upon the blank at the point 9. The laterally extending flaps 5 are then turned inward over 50 the explosive approximately at the points indicated by the lines a. The tablet is then rolled in the direction longitudinal the body 4 of the blank, the blank doubling approximately at the points indicated by the dotted 55 lines b. When the rolling has reached the

point 10 of the blank, the flaps 6 are bent upwardly approximately at the points indicated at c. When the blanks are in this upward position the rail-engaging strap 2 is passed through the openings 7, after which 60 the ends of the flaps 6 are turned over inwardly approximately on the lines d. The rolling then continues the blank doubling approximately at the points indicated by the lines e until the end of the blank is 65 reached. The blank is coated with suitable cement as indicated in Fig. 4, preferably of a water-proof nature, so that the parts are cemented in their folded and wrapped positions around the explosive tablet 8 forming 70 a complete case therefor. After the tablet is inclosed in the case made from the blank as described, it may be dipped into a suitable water-proofing compound for the purpose of further inclosing it against the entrance of moisture or rain.

While it is preferred to provide the flaps 6 with openings 7 for the rail-engaging strap, the openings may be omitted and the rail engaging strap attached in any desired 80 way to the outside of the case.

In the construction here shown, the intermediate flaps 6 form a double closure for the ends of the explosive, as shown in Fig. 2, and if only one closure is desired for the 85 ends of the explosive and the rail-engaging strap attached in some other way, the intermediate flaps 6 may be omitted.

Having thus described my invention, what I claim and desire to secure by Letters Patent is—

1. A railway signal torpedo composed of an explosive tablet rolled in a blank, said blank having an elongated body portion, one extremity of the body portion having oppositely extending lateral flaps of a width equal to the width of the tablet and of a length to extend around the ends of the tablet and over on its body portion, the blank having intermediate laterally extending flaps of substantially the same width and length as the said end flaps, the end and intermediate flaps located a distance apart equal to the width of the tablet and twice its thickness to make a double end closure 95 for the tablet, the remainder of the elongated portion of the blank wrapped around the doubled end flaps and cemented, thus forming a closure for the tablet.

2. A railway signal torpedo composed of 110

an explosive tablet and a blank, the blank having an elongated body-portion, one end of which is provided with laterally extending flaps, and also intermediately located 5 laterally extending flaps, all of said flaps having a width equal to the width of the tablet, the latter flaps having openings for a rail-engaging strap, the ends of the flaps doubled around the end of the explosive, the 10 body-portion then wrapped therearound and the intermediate flaps turned up to receive the rail-engaging strap and also dou-

bled around the ends of the explosive, the remainder of the body-portion wrapped around and cemented forming a closure for 15 the explosive, and a rail-engaging strap passing through the said strap openings.

In testimony whereof I hereunto affix my signature in the presence of two witnesses,

FRANK DUTCHER.
